UNITED STATES PATENT OFFICE.

SWINFEN BRAMLEY-MOORE, OF BLOOMSBURY, ENGLAND.

LIQUID-METER.

No. 879,141.

Specification of Letters Patent.

Patented Feb. 18, 1908.

Application filed May 10, 1907. Serial No. 372,901.

To all whom it may concern:

Be it known that I, SWINFEN BRAMLEY-MOORE, a subject of the King of Great Britain and Ireland, residing at 26 Russell Square, Bloomsbury, in the administrative county of London, England, have invented a new and useful Improvement in Liquid-Meters, of which the following is a full and complete specification.

10 This invention relates to an improved construction of liquid meter.

In the accompanying drawings which illustrate this invention:—Figures 1, 2 & 3 are views in sectional elevation showing one 15 from of the apparatus; Fig. 1 showing the parts in the positions they occupy when the liquid has just commenced to flow into the measuring vessel; Fig. 2 showing the parts in the positions they occupy when the measuring vessel is nearly full, the inlet valve 20 having shut off the supply; and Fig. 3 showing the parts in the positions they occupy when the measuring vessel has descended and the bulk of the fluid passed out of the 25 measuring vessel into the case. Fig. 4 is a view in side elevation, partly in section, showing a modification, the respective parts being in the same positions as they are shown in Fig. 1.

30 Throughout the views similar parts are marked with like letters of reference.

Referring to Figs. 1, 2 & 3. In a suitable case *a* is a rising and falling vessel *b*—hereinafter called the “measuring vessel”. This 35 vessel is carried by two arms *h* (only one of which is seen in the drawing) pivoted at *h*¹ to the case *a*. On or in the top of the case *a* is a chamber *c* provided with an inlet passage *a*¹ leading into said chamber, the opening into 40 said chamber being closed by a spring-controlled valve *d*. The chamber *c* is provided with a siphon outlet pipe *a*² leading into the case *a* above the vessel *b*. Mounted in suitable guides in both the chamber *c* and the 45 vessel *b* is a vertically arranged rod *e*² adapted to operate the valve *d* through the rocking lever *e*¹ pivoted on the exterior of the chamber *c*, and at a suitable position on this rod is a shoulder or collar. On the bottom of the 50 vessel *b* are pivoted two rocking levers *e*¹ *e*¹ the inner ends of which contact the shoulder or collar on the rod *e*² and the outer ends are adapted to engage the bottom of the vessel *b*. In the measuring vessel *b* is a float *e* 55 which, when the said vessel is empty, rests on the outer ends of the levers *e*¹ *e*¹ and so op-

erates to keep the valve *d* open. In the bottom of the measuring vessel is an opening leading into the lower part of the case *a*, the said opening being closed by a valve *f* adapted to be opened by the descent of the measuring vessel which causes the stem *f*¹ of the valve to contact the bottom of the case *a*. The lower part of the case *a* is provided with an outlet siphon pipe *l*. Pivoted at *g*² to the 60 case *a* are a pair of counterweights *g* and *g*¹ each carried by an arm *g*². These counterweights are connected to the measuring vessel by the arm *g*¹ and the link *k* connected to the arms *h*. 65

The weight of the counterweight *g* is equal to a predetermined portion, say five-eighths, of the weight of the liquid admitted to the measuring vessel at each operation of the apparatus, and the weight of the counterweight *g*¹ is slightly in excess of the weight of the measuring vessel and its appurtenances. In the case *a* is a float *j* which is connected by a link *j*¹ with an arm *j*² pivoted to the case *a*, preferably at the same point *h*¹ as the levers 70 *h*. The free end of the arm *j*² is shaped to engage a stud *g*⁵ on the counterweight *g* so as to lock it in its raised position until the vessel *b* has discharged the bulk of its contents. In order to prevent a vacuum being formed in 75 the chamber *c* it is provided with a small air hole such as *a*³.

The action of the apparatus is as follows:— Assuming the apparatus to be empty and that liquid is permitted to flow into the pipe 90 *a*¹, it passes through the valve *d* into the chamber *c* and from thence through the siphon pipe *a*² into the measuring vessel *b* which is at its highest position. As the liquid accumulates in the vessel *b* it causes the 95 float *e* to rise, which thereby releases the rod *e*² and allows the valve *d* to be closed by its spring, thereby shutting off the supply of liquid when the predetermined quantity has passed into the chamber *c*. When a predetermined quantity of fluid in the chamber *c* has passed into the vessel *b* its weight overbalances the counterweights *g* and *g*¹ and the vessel begins to sink, and when it reaches its lowest position the counterweights have been 100 raised to such a position that the center of gravity of the counterweight *g* is approximately in a vertical plane with the pivot on which it swings so that its influence is negative. As the vessel *b* sinks and reaches its 105 lowest position the stem *f*¹ of the valve *f* contacts the bottom of the case *a* and thus opens 110

the said valve and allows the liquid to flow out of the measuring vessel *b* into the lower part of the case *a*. As the liquid rises in said case the float *j* operates to lock the counterweights 5 and so prevent them raising the said vessel and restoring it to its highest position. After this locking is effected the outlet siphon pipe comes into action and empties the case which causes the float *j* to sink and unlock the counterweights, thereby allowing the vessel to be raised. As the liquid passes out of the vessel *b* the float *e* sinks and coming in contact with the rockers *e*¹ operates them so as to lift the rod *e*² so that when the 10 vessel rises the said rod *e*² contacts the lever *e*³ and thus opens the valve *d*. In due course the measuring vessel is again filled with liquid, when the sequence of operations is automatically repeated until either the 15 supply of liquid is cut off or the flow of liquid out of the case *a* is stopped automatically by the level of the liquid in a receiver reaching such a level as to stop the action of the siphon outlet pipe *l*. 20

25 In the modification shown by Fig. 4 the float *e* operates the valve *d* through an arm *n* which is pivoted to the case *a* and connected to the float *e* by a link *n*¹. The arm *n* is connected with one or both of the levers *h* by a 30 lever *n*² pivoted at *n*³ to one or both of the levers *h*, the one end of said lever *n*² engaging the free end of the arm *n* and the other end engaging a finger *n*⁴ sliding in the top of the case *a* and adapted to contact the valve *d* so 35 as to operate to open it. To prevent any possibility of the measuring vessel partially descending from its highest position and then forming a perfect balance with the counterweight and so remaining in a midway position, the main outlet *a*² is so arranged as not 40 to be capable of completely emptying the chamber *c* and an additional outlet is provided capable of completely emptying the said chamber, the said auxiliary outlet being 45 closed by an auxiliary valve *d*¹ which is coupled with the valve *d*, through the finger *n*⁴, by means of the rocking lever *n*⁵. The valve *f* is opened by a projection *f*² on its head engaging a stop *a*⁴ on the side of the case *a* as 50 the measuring vessel descends. The float *j* is connected through the link *j*¹ with an arm *m* pivoted on the pivotal shaft *g*³ carrying the arms of the counterweights, and to which the arm *g*⁴ is fixed, so that it operates directly to 55 control the time at which the measuring vessel will rise.

The apparatus is provided with any suitable recorder; but this forms no part of the present invention.

60 What I claim as my invention, and desire to secure by Letters Patent, is:—

1. A liquid meter comprising a suitable case, a rising and falling measuring vessel in said case, an inlet to said case, a valve controlling said inlet, a float in the measuring

vessel, means for connecting the float with the inlet valve whereby the rise and fall of said float operates to close and open the inlet valve, an outlet valve in the bottom of the measuring vessel leading into the case, an 70 arm pivoted to the case, a counterweight carried by said arm, means for connecting the counterweight with the measuring vessel, a locking device for holding the counterweights in their highest positions and thereby retaining the measuring vessel in its lowest position, a float in the case, means for connecting the float with the said locking device, and an outlet from the said case, as set forth. 75

2. A liquid meter comprising a rising and falling measuring vessel in a suitable case, a chamber located above said case, an inlet to said chamber, a valve in said inlet, an outlet from said chamber into the case above the measuring vessel, a float in the measuring vessel, means for connecting the float with the inlet valve so that when the predetermined quantity of liquid has passed into the measuring vessel the valve is closed, an outlet valve in the bottom of the measuring vessel 90 adapted to be operated by contact with the case, arms pivoted to the case, counterweights carried by said arms, means including the arms for connecting the counterweight with the measuring vessel, a locking device 95 for holding the counterweights in their highest positions and thereby retain the measuring vessel in its lowest position, a float in the case, means for connecting said float with said locking device, and an outlet from the 100 said case, as set forth.

3. A liquid meter comprising a suitable receptacle, a rising and falling measuring vessel in said receptacle, a chamber located above said receptacle, an inlet to said chamber, a valve in said inlet, an outlet from said chamber into the receptacle above the measuring vessel, a float in the measuring vessel, means for connecting the float with the inlet valve whereby the rise and fall of said float 105 operates to close and open the inlet valve, an outlet valve in the bottom of the measuring vessel leading into the receptacle adapted to be opened by contact with the said receptacle, an arm pivoted to the case, a counterweight carried by said arm, means including the arm for connecting the counterweight with the measuring vessel so that said counterweight is lifted by the measuring vessel as it descends, means for locking the counterweight in its highest position and retaining the measuring vessel in its lowest position for a predetermined period, and an outlet pipe from the said case, as set forth. 110

4. A liquid meter comprising a rising and falling measuring vessel in a suitable case, a chamber located above said case, an inlet to said chamber, a valve in said inlet, a siphon pipe leading from said chamber to said case, a float in the measuring vessel, means for con- 125

necting the float with the inlet valve, an outlet valve in the bottom of the measuring vessel adapted to be operated by the descent of the vessel, an arm pivoted to the case, a counterweight carried by said arm, means including the arms for connecting the counterweight with the measuring vessel, a float in the case connected with the counterweight and operating to prevent the counterweight from falling and therefore the measuring vessel from

rising before the measuring vessel is empty, and a siphon outlet pipe from said case, as set forth.

In testimony whereof I have signed my name in the presence of two subscribing witnesses. 15
